CLAIM

The ornamental design for outsole for athletic shoe,
substantially as shown and described.

DESCRIPTION

FIG. 1 is a bottom plan view of an outsole for athletic
shoe showing our new design;

FIG. 2 is a top plan view thereof;

FIG. 3 is a left side elevational view thereof, the broken
line showing of a shoe being environmental only and
forming no part of the claimed design;

FIG. 4 is a right side elevational view thereof;

FIG. 5 is a front elevational view thereof; and

FIG. 6 is a rear elevational view thereof.

FIG. 1.

FIG. 2.

FIG. 3.

FIG. 4.

FIG. 5.

FIG. 6.
